UNITED STATES PATENT OFFICE.

JOHN R. RHINEHART, OF CARLISLE, ASSIGNOR OF ONE-HALF TO JOHN O. DILL, OF ALLEN, PENNSYLVANIA.

BUILDING.

SPECIFICATION forming part of Letters Patent No. 251,637, dated December 27, 1881.

Application filed October 18, 1881. (No model.)

To all whom it may concern:

Be it known that I, J. R. RHINEHART, a citizen of the United States of America, residing at Carlisle, in the county of Cumberland and State of Pennsylvania, have invented certain new and useful Improvements in the Construction of Buildings; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to the construction of buildings; and it consists in certain improvements therein having reference to the strength and durability of the structure, as herein shown and described.

20 In the accompanying drawings, which form a part of this specification, Figure 1 represents in perspective a building having my improvements, parts of the building being removed. Fig. 2 is a perspective view of the foundation, 25 showing the bottom of the same and attachments. Fig. 3 illustrates in section the manner of securing the rafters.

In the said drawings, A designates the foundation of the building, having the sills B resting thereon.

30 C indicates the wall-plate, the rafters D being fixed thereto in the ordinary position.

In constructing the building iron rods *a* are placed in a vertical position in the frame, as shown, said rods passing through the wall-plate C and downward through intermediate timbers, through the sills B and the foundation, also through apertures in the iron bars or plates *b*, placed under the foundation and 35 bolted at the corners, as shown in Fig. 2. The said rods *a* are keyed or secured by burrs *c* under the bars *b*, and drawn and secured above by means of burrs and bars or plates *d*, thus 40 bracing the building and binding the same and its foundation firmly together. Burrs *e* are formed at joints in the rods *a*. The rafters D are also firmly secured in place by means 45 of rods *f*, each of said rods passing over a span of rafters, and being usually sunk or placed in

a groove therein. The ends of each rod *f* are 50 passed down through the wall-plate C, and after the rod is tightly drawn are secured by burrs *g* under the wall-plate; or the ends of rod *f* may be passed through the rafter, which is then usually provided with plates *h* at the 55 points where the rod passes through, and the rod being secured by burrs, as shown at *x* in Fig. 3. When the rods *f* are secured as last stated the ends of the rafters are usually bolted to the wall-plate C.

60 The improvement described may be applied to buildings already erected, the vertical rods being placed against the walls of the building or sunk therein. In such application of the rods iron pins provided with eyes are passed 65 through the wall-plate or walls of the building and secured on the inside with burrs, or they may be screwed into the walls. The rods are passed through the eyes of the pins and secured at their upper extremities with burrs, being fastened at their lower extremities by means 70 of stones, iron plates, or bars in the ground.

The invention may be applied to buildings of any kind of material, and in case of a building without any independent foundation the 75 vertical rods may be secured below by extending them below the surface of the ground and fastening them to horizontal bars of iron.

70 The construction described greatly increases the strength of the building, which may be 80 safely built of lighter and less expensive material, the material saved being enough to balance the cost of the additional improvement.

Buildings constructed with the improvement described are well calculated to endure the 85 shocks of gales and torrents, as the force necessary to damage the building to any great extent would have to be sufficient to overturn the whole building, including the foundation. Thus in many instances the structure might 90 be saved if this construction were adopted.

I claim—

1. In combination with the rafters of a building, the rods *f*, running over the spans of rafters and having their ends secured substantially as set forth.

2. In combination with the rafters of a building, rods *f*, passing along and over the rafters

and through the wall-plate, said rods being secured in place substantially as and for the purposes described.

3. In combination with the rafters and rods 5 *f* and the wall-plates, the vertical rods *a* and plates *b*, constructed and arranged as and for the purpose set forth.

In testimony whereof I affix my signature in presence of two witnesses.

JOHN R. RHINEHART.
